CRYSTAL OVEN

August E. Miller, Cliffside Park, N. J.

Application December 5, 1946, Serial No. 714,275

9 Claims. (CL. 171—327)

1

The invention relates to a piezo crystal oven and holder. It is desirable if not essential that the crystal used in oscillating circuits be stabilized with respect to its oscillating frequency. One of the factors which affect the frequency of oscillation of a crystal is the temperature at which it operates. For this reason it is customary to provide means for maintaining the crystal at a predetermined operating temperature so that there will be no variation in frequency response because of temperature changes.

Crystal controlled oscillator circuits constitute a part of the radio and radar equipment on aircraft which are subject to wide variations in temperature. It is also important that crystal ovens for aircraft service occupy a minimum of space. This requires an efficient utilization of the space required for the crystal oven.

It is an object of the invention to construct a crystal oven which effectively maintains the temperature of the crystal at the desired operating temperature and a crystal holder which utilizes space efficiently so that the oven has minimum dimensions.

Another object is to construct a crystal oven and holder in which a fast heater with a control thermostat is utilized to quickly raise the temperature of the oven to approximately the desired operating temperature, and a slow and more accurate heater and control thermostat for accurately maintaining the operating temperature of the crystal within the oven.

Another object is to construct a crystal oven and holder which can be easily assembled and disassembled for repair or replacement of parts.

Other objects of the invention will be more apparent from the following description when taken in connection with the accompanying drawing, which illustrates a preferred embodiment thereof, in which:

Figure 1 is a cross-sectional view through the oven.

Figure 2 is a top view of the crystal holder.

Figure 3 is a cross-section through the holder taken on line 3—3 of Figure 2.

Figure 4 is a circuit diagram of the electrical connections of the heaters and their thermostats and of the crystals.

The crystal oven includes a casing which may be constructed in any suitable fashion, that illustrated being made up of several parts, including a side wall 10, a top cover 11, and a base 12, which parts may be of heat insulating material such as "Bakelite." The case may be further heat insulated by a metal film 13 upon the sides and

2

top which may be secured thereto and pads 14 such as of glass wool. The base carries a connecting base 15 having a series of contact prongs 16 which are electrically connected with the various elements of the oven.

Within the case is a crystal holder 19, shown in cylindrical form with flat top and bottom faces, having at least one and preferably two crystal cavities 20. The pair of crystal cavities are spaced upon each side of the center of the holder and spaced from each other. These crystal cavities preferably extend completely through the crystal holder between the flat faces thereof. The crystal holder is of metal, and preferably a light weight metal such as aluminum, because of the good heat conducting properties of metal which readily transmits heat therefrom to the crystal structure.

A slow heater thermostat cavity 21 extends diagonally from the bottom edge of the holder to the opposite top edge between the crystal cavities. A fast heater thermostat cavity 22 also extends into the crystal holder from one edge thereof and between the crystal cavities and intersects the slow heater thermostat cavity 21. The fast heater thermostat cavity is adjacent to the top face of the holder. A slow heater thermostat 23 is mounted in the diagonal cavity and a fast heater thermostat 24 is mounted in its cavity 22. A pair of spaced holes 27 extend between the faces of the crystal holder 19 and in the top face of the holder is a groove 28 extending at least between the holes. The holes are adjacent the end of the crystal cavities. A fast heater 29, which is preferably U-shaped in form, has its legs extending through the holes and its connecting portion lies within the groove 28. An electrically insulating glass fabric 30 extends around the crystal holder and a slow heater 31 is wound around the holder and fabric. This heater winding preferably is non-inductive with parallel wires and the screws 32 are the terminals therefor. A screw 33 holds the looped end of the slow heater. Adjustment of the position of the insulators 37 upon the looped end of the slow heater adjusts the position of the crossed or shorted ends and thereby enables the length and hence the resistance of this heater to be accurately adjusted. It is connected in series with the slow heater thermostat 23 and the U-shaped heater is connected in series with the fast heater thermostat 24. The two heaters and particularly the fast heater brings the temperature of the holder and crystal assembly rapidly to the desired operating temperature of about 70 degrees whereupon the slow heater

accurately maintains the parts at this temperature with the aid of the metallic crystal holder which serves as a heat reservoir or stabilizer. Suitable wires W connect the heaters in series with their respective thermostats and with the contact pins or prongs 16.

A crystal assembly 34 is mounted in each crystal cavity 20, which assembly may be of any suitable kind. Such assemblies generally include a crystal, an electrode mounted upon each side thereof, and a case retains the electrodes and crystal in assembled relation. The crystal holder has a top plate 35 secured to the top flat face of the holder in order to enclose the cavities therein. A bottom plate 36 is secured to the bottom flat surface of the holder to enclose this end thereof. Suitable holes are provided through the bottom plate for connecting wires to the electrodes of the crystal assemblies and to make connection with the fast heater.

A heat insulating baffle plate 39 is secured to the bottom plate 36 such as by screws 38 and is spaced therefrom by spacing washers 40. The baffle plate also is provided with holes for the passage of wires to the crystal electrodes and to the heaters or their thermostats. The baffle plate is in turn secured to the base 12 such as by screws 43 so that the entire crystal holder assembly is secured thereto. The baffle plate is spaced from the base 12 by spacing washers 41.

Suitable wires W extend from the prongs 13 to the crystal electrodes and to the thermostats and heaters as well as between the heaters and thermostats so that the entire crystal oven may be plugged into a socket and thereby establish electrical connection between the various parts thereof and the circuit of which it will form a part.

The crystal oven provides a compact arrangement of the parts thereof as well as a pair of heaters for rapidly raising the temperature to the desired operating temperature and then accurately maintaining the same.

This invention is presented to fill a need for improvements in crystal oven. It is understood that various modifications in structure, as well as changes in mode of operation, assembly, and manner of use, may and often do occur to those skilled in the art, especially after benefiting from the teachings of an invention. Hence, it will be understood that this disclosure is illustrative of performed means of embodying the invention in useful form by explaining the construction, operation and advantages thereof.

What is claimed is:

1. A piezo electric crystal holder comprising a metallic housing of such dimensions as to enclose heater and control elements and at least one piezo crystal assembly, at least one crystal cavity therein to receive a crystal assembly including the piezo crystal, crystal electrodes and case, a slow electric heater coil wound around the metallic housing, spaced holes through the housing, a fast electric heater extending into the spaced holes, a pair of thermostat cavities in the housing, and a thermostat in each cavity, one thermostat being connected with each heater to control the current supplied to its respective heater.

2. A piezo electric crystal holder comprising a metallic housing of such dimensions as to enclose heater and control elements and at least one piezo crystal assembly, at least one crystal cavity therein to receive a crystal assembly including the piezo crystal, crystal electrodes and case, a

slow electric heater coil wound around the metallic housing, a pair of spaced holes through the housing, a groove in one face of the housing extending between the holes, a U-shaped fast electric heater having its arms extending into the spaced holes and the connecting portion received within the groove, a pair of thermostat cavities in the housing, and a thermostat in each cavity, one thermostat being connected with each heater to control the current supplied to its respective heater.

3. A piezo electric crystal holder comprising a cylindrical metallic housing of such dimensions as to enclose heater and control elements and a pair of piezo crystal assemblies, a pair of crystal cavities therein spaced from the center of the housing, each cavity receiving a crystal assembly including the piezo crystal, crystal electrodes and case, a slow electric heater coil wound around the cylindrical surface of the metallic housing, a pair of spaced holes through the housing and parallel with the crystal cavities and adjacent thereto, a groove in one face of the housing extending between the holes, a U-shaped fast electric heater having its arms extending into the spaced holes and the connecting portion received within the groove, a pair of thermostat cavities in the housing between the crystal cavities, and a thermostat in each cavity, one thermostat being connected with each heater to control the current supplied to its respective heater.

4. A piezo electric crystal holder comprising a cylindrical metallic housing of such dimensions as to enclose heater control elements and a pair of piezo crystal assemblies, a pair of crystal cavities therein spaced from the center of the housing, each cavity receiving a crystal assembly including the piezo crystal, crystal electrodes and case, a slow electric heater wound around the cylindrical surface of the metallic housing, a pair of spaced holes through the housing and parallel with and adjacent to the crystal cavities, a groove in one face of the housing extending between the holes, a U-shaped fast electric heater having its arms extending into the spaced holes and the connecting portion received within the groove, a thermostat cavity in the housing extending from one edge of the metallic housing diagonally to the other edge and between the crystal cavities, a second thermostat cavity extending from the circumference of the metallic housing to the first thermostat cavity and located adjacent to a face of the metallic housing, and a thermostat in each cavity, each thermostat being connected with its respective heater to control the current supplied thereto.

5. A piezo electric crystal oven comprising a metallic housing having flat top and bottom faces and of such dimensions as to enclose heater and control elements and at least one piezo crystal assembly; at least one crystal cavity therein to receive a crystal assembly including the piezo crystal, crystal electrodes and case; a slow electric heater coil wound around the metallic housing, spaced holes through the housing, a fast electric heater extending into the spaced holes, a pair of thermostat cavities in the housing, a thermostat in each cavity, one thermostat being connected with each heater to control the current supplied to its respective heater, a top and bottom metallic cover secured to each face of the housing, an insulating baffle plate spaced from the bottom cover, an insulated case surrounding the housing including a base having electrical connecting prongs, and wires connect-

ing the prongs with the heaters and the crystal electrodes.

6. A piezo electric crystal oven comprising a metallic housing having flat top and bottom faces and of such dimension as to enclose heater and control elements and at least one piezo crystal assembly; at least one crystal cavity therein to receive a crystal assembly including the piezo crystal, crystal electrodes and case; a slow electric heater coil wound around the metallic housing, a pair of spaced holes through the housing, a groove in one face of the housing extending between the holes, a U-shaped fast electric heater having its arms extending into the spaced holes and the connecting portion received within the groove, a pair of thermostat cavities in the housing, a thermostat in each cavity, one thermostat being connected with each heater to control the current supplied to its respective heater, a top and bottom metallic cover secured to each face of the housing, an insulating baffle plate spaced from the bottom cover, an insulated case surrounding the housing including a base having electrical connecting prongs, and wires connecting the prongs with the heaters and the crystal electrodes.

7. A piezo electric crystal oven comprising a cylindrical metallic housing having flat top and bottom faces and of such dimensions as to enclose heater and control elements and a pair of piezo crystal assemblies, a pair of crystal cavities therein spaced from the center of the housing; each cavity receiving a crystal assembly including the piezo crystal, crystal electrodes and case; a slow electric heater coil wound around the cylindrical surface of the metallic housing, a pair of spaced holes through the housing and parallel with the crystal cavities and adjacent thereto, a groove in one face of the housing extending between the holes, a U-shaped fast electric heater having its arms extending into the spaced holes and the connecting portion received within the groove, a pair of thermostat cavities in the housing between the crystal cavities, a thermostat in each cavity, one thermostat being connected with each heater to control the current supplied to its respective heater, a top and bottom metallic cover secured to each face of the housing, an insulating baffle plate spaced from the bottom cover, an insulated case surrounding the housing including a base having electrical connecting prongs, and wires connecting the prongs with the heaters and the crystal electrodes.

8. A piezo electric crystal oven comprising a cylindrical metallic housing having flat top and bottom faces and of such dimension as to enclose heater control elements and a pair of piezo crystal assemblies, a pair of crystal cavities therein spaced from the center of the housing; each cavity receiving a crystal assembly including the piezo crystal, crystal electrodes and case; a slow electric heater wound around the cylindrical surface of the metallic housing, a pair of spaced holes through the housing and parallel with and adjacent to the crystal cavities, a groove in one face of the housing extending between the holes,

a U-shaped fast electric heater having its arms extending into the spaced holes and the connecting portion received within the groove, a thermostat cavity in the housing extending from one edge of the metallic housing diagonally to the other edge and between the crystal cavities, a second thermostat cavity extending from the circumference of the metallic housing to the first thermostat cavity and located adjacent to a face of the metallic housing, a thermostat in each cavity, each thermostat being connected with its respective heater to control the current supplied thereto, a top and bottom metallic cover secured to each face of the housing, an insulating baffle plate spaced from the bottom cover, an insulated case surrounding the housing including a base having electrical connecting prongs, and wires connecting the prongs with the heaters and the crystal electrodes.

20 9. A piezo electric crystal oven comprising a cylindrical metallic housing of such dimensions as to enclose heater control elements and a pair of piezo crystal assemblies, a pair of crystal cavities therein spaced from the center of the housing, each cavity receiving a crystal assembly including the piezo crystal, crystal electrodes and case, a slow electric heater wound around the cylindrical surface of the metallic housing, a pair of spaced holes through the housing and parallel with and adjacent to the crystal cavities, a groove in one face of the housing extending between the holes, a U-shaped fast electric heater having its arms extending into the spaced holes and the connecting portion received within the groove, a thermostat cavity in the housing extending from one edge of the metallic housing diagonally to the other edge and between the crystal cavities, a second thermostat cavity extending from the circumference of the metallic housing to the first thermostat cavity and located adjacent to a face of the metallic housing, and a thermostat in each cavity, each thermostat being connected in series with its respective heater to control the current supplied thereto,

45 a top and bottom metallic cover secured to each face of the housing, an insulating baffle plate spaced from the bottom cover, an insulated case surrounding the housing including a base having electrical connecting prongs, and wires connecting the prongs with the heaters and the crystal assemblies.
